UNITED STATES PATENT OFFICE.

CHARLES V. HATZFELD, OF MINERAL WELLS, TEXAS.

OPENER AND CLOSER FOR JARS AND THE LIKE.

Application filed July 5, 1924. Serial No. 724,458.

My invention relates to an improved closer and opener for jars and other vessels; and the object is to provide a simple tool by which such vessels as jars and the like may be quickly and easily closed and opened with little effort and which is adjustable to engage the tops of various sizes, from the smallest to the largest and which is provided with simple means for adjusting the tool to any size lid or cover. Other objects and advantages will be fully explained in the following description and the invention will be more particularly pointed out in the claims.

Reference is had to the accompanying drawings which form a part of this application.

Fig. 1 is a plan view of the tool. Fig. 2 is a side elevation of the same. Fig. 3 is an inverted plan view of the gripping members, parts being broken away. Fig. 4 is an enlarged detail view of the adjustable gripping member.

Similar characters of reference are used to indicate the same parts throughout the several views.

The tool is provided with a frame 1 substantially rectangular with one side formed into a gripping member, having the parts 2 set at a slight angle to the sides 1 and having a portion 3 which is at angle to the parts 2 to make a converging space, the object being to make the gripping member engage different sizes of lids or covers. The frame is provided with guide members 4 which may be formed integral with the frame members 1 and 2. The adjustable gripping member 5 has notches or cut-outs 6 to receive the guide members 4. The gripping member 5 is adjusted by a screw shaft 7 which is screwed through the member 1 and has a swivel connection with the member 3. The frame 1 has a bearing member 8 for the screw shaft 7 and this bearing member 8 may be made integral with the frame member 1. A handle 9 is provided for operating the screw shaft 7. The gripping member 5 slidably engages the guide members 4 and this gripping member 5 is threaded to travel on the screw shaft 7. The lower parts of the gripping members 3 and 5 are provided with teeth 9. The teeth are arranged at inclines near the outer ends of the gripping members so that they will tend to press the lid or cover towards the center of the gripping members. The parts thus described

constitute the means for closing and opening jars or other vessels which have detachable lids or covers with screw or cam fastenings.

In operation the tool is placed on top of the lid or cover with the gripping members 5 and 2 and 3 extended downwardly on the sides. The gripping member 5 is then tightened on the lid or cover of the vessel by turning the screw shaft 7. The bearing member and handle 8 can then be used to screw the top or lid for closing or opening the vessel.

The tool is also adapted for opening sealed cans or other vessels. A spear or point 10 may be formed integral with or attached to the frame or gripping member 3. This spear 10 is off-set out of the plane of the frame so that when the spear 10 is projected down through the tin, the frame 1 can be rotated about the top of the can in close proximity thereto. A cutting blade 11 and a guide 12 may be formed integral with or attached to the gripping member 5.

In operation the spear or point 10 is projected through the center of the top of the can and then the blade 11 and the guide 12 are adjusted by the screw shaft so that the guide 12 will move just outside of the can and the blade 11 projected down through the tin next to the side wall. The tool is then held on the can and the tool rotated by the handle 8 to cut the top of the can out, and leave the edge smooth.

The tool is also provided with a bottle opener 13 which may be attached to the side of the tool as shown. This opener 13 may be used in the ordinary manner for opening bottles or removing caps of soda pop bottles or caps from various sealed receptacles.

The shaft 7 is prevented from axial movement in the frame members 1 and 3 by a shoulder 14 at one end and a washer 15 with a pin 16 at the frame member 1.

Various changes in the construction, arrangement, and proportions of the several parts may be made without departing from my invention.

What I claim is:—

1. A vessel opener and closer comprising a frame having an opening in one end and having the front end angular for forming a gripping member and longitudinal guide members integral with said frame, a screw shaft operating in said opening, and a curved gripping member engaged by said shaft and actuated thereby and having cut-outs for re-

- ceiving said guide members whereby said curved gripping member is guided in its longitudinal move, said gripping member and said angular frame member having inclined teeth. 5
2. A vessel opener and closer comprising a frame having an opening in one end and having the front end angular and converging towards the front for forming a gripping member, inclined teeth formed thereon, a screw shaft operating through said opening and having a swivel connection with said gripping member, and a curved gripping member co-operating with said angular gripping member and provided with inclined teeth for co-operating with the teeth of said angular gripping member. 10
3. A vessel opener and closer comprising a frame having an opening through its rear end and having at its front end two angular integral members converging towards the front and provided with inclined teeth to form a gripping member, longitudinal guide members rigid with the front and rear ends 15 of said frame, a curved gripping member provided with inclined teeth co-operating with said angular gripping member and hav-
- ing recesses receiving said guide members, and a screw shaft operating through said rear frame member and having a swivel connection with said front member and operating in said curved gripping member for actuating said gripping member. 20
4. A vessel closer and opener comprising an opening in the rear end and having two angular front end members converging towards the front and provided with inclined teeth and forming gripping members, longitudinal guide members integral with said front and rear members, a curved co-operating gripping member provided with recesses for said guide members and with inclined teeth co-operating with said angular gripping members and provided with a threaded opening therethrough, a screw shaft operating loosely through said rear end and engaging the threaded opening in said curved gripping member and having a swivel connection with said front end, and a bearing for said screw shaft. 25

In testimony whereof, I set my hand this 26th day of March, 1924.

CHARLES V. HATZFELD.
